By Franklin H. Shapley

Attorney

UNITED STATES PATENT OFFICE.

HARRY G. BERKELEY, OF WASHINGTON, DISTRICT OF COLUMBIA.

APPARATUS FOR CLEANING BLACKBOARD-ERASERS.

No. 895,232.

Specification of Letters Patent.

Patented Aug. 4, 1908.

Application filed April 4, 1908. Serial No. 425,202.

To all whom it may concern:

Be it known that I, HARRY G. BERKELEY, a citizen of the United States, residing at Washington, in the District of Columbia, have invented certain new and useful Improvements in Apparatus for Cleaning Blackboard-Erasers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in Apparatus for cleaning blackboard erasers and comprises essentially a frame-work upon which a rotary brush is mounted and in the provision of an endless carrier having cleats projecting therefrom adapted to engage the opposite ends of the eraser while the brush is cleansing the eraser as it is passed underneath the brush.

20 The invention comprises various details of construction, combinations and arrangements of parts which will be hereinafter fully described and then specifically defined in the appended claims.

I illustrate my invention in the accompanying drawings, in which:—

Figure 1 is a side elevation of my improved apparatus for cleaning blackboard erasers. Fig. 2 is a longitudinal sectional view through the apparatus, and Fig. 3 is an end view.

Reference now being had to the details of the drawings by letter, A—A designates legs supporting a top B and forming a frame-work. C is a brush mounted in suitable bearings upon said top and adapted to turn in an opening D formed in said top. A shaft E is journaled in suitable bearings in the cross-pieces F connecting said legs, and G designates a balance wheel which is fixed to the shaft E and has a grooved pulley H either integral or fixed thereto. J designates a band which passes about said grooved pulley H and also about a pulley K fixed to the brush C, whereby the latter may be rotated. A crank N is fixed to the shaft E and a pitman O is pivotally connected to said crank and also to the tread lever R, which latter is hinged at S to the frame-work.

A boxing or trough, designated by letter

T, is mounted immediately underneath the top B and has an inclined slot T' leading 55 therein through which the erasers to be cleaned are adapted to be passed. Mounted to travel upon the sprocket wheels Q is an endless conveyer belt I having cleats I', made preferably of metal of any suitable kind, 60 designed to move through openings in the ends of said boxing or trough, said cleats being a distance apart equal to the length of an eraser between which the erasers are held as they are being cleansed. A receptacle P is 65 mounted near one end of the conveyer and into which the erasers fall as the conveyer turns about the sprocket wheels. Fixed to a projecting end of the shafts Q', upon which the sprocket wheels Q are mounted, is a hand 70 wheel Q' whereby one shaft or the other may be rotated for the purpose of moving the conveyer so as to bring the various erasers to be cleansed underneath the brush. In said boxing opposite the ends of the brush are the 75 windows L, whereby the operator may see when an eraser comes underneath the brush.

In operation, the erasers are slipped through the slot T' upon the endless conveyer and the conveyer is moved forward by operating the 80 hand wheel Q', and the brush started to rotate by the tread power having connection therewith. The operator by turning the wheel Q' will cause the endless carrier to move and bring the erasers to be cleansed 85 successively underneath the rapidly rotating brush. The brush, an edge view of which is shown in Fig. 3 of the drawings, is narrow and preferably of a width equal to the width of the eraser being cleansed. As the brush 90 rotates, preferably in a direction opposite the travel of the endless carrier upon which the erasers are mounted, the latter will become thoroughly cleansed as it passes underneath the brush. If desired, the operator may 95 bring the endless carrier to a stand-still if it should be desired to allow the brush to operate longer upon each eraser. When the erasers approach the end of the conveyer, they drop into the receptacle P, provided to 100 catch the same.

What I claim to be new is:—

An apparatus for cleansing black-board erasers, comprising a frame-work, a rotatable brush mounted thereon, a trough underneath 105 and adjacent to the top of said frame, said

trough having openings at its ends, an endless conveyer, sprocket wheels upon which the same travel, said conveyer moving through the apertures in the ends of said trough, means for operating said conveyer chain, a chute leading through the top of the frame into said trough, as set forth.

In testimony whereof I hereunto affix my signature in the presence of two witnesses.

HARRY G. BERKELEY.
